UPRIGHT PIANO ACTION AND PEDAL
ASSEMBLYHumbert Thurston Scott-Huntington,
Belmar, N. J.

Application July 15, 1946, Serial No. 683,634

11 Claims. (Cl. 84—240)

1

My invention relates to new and useful improvements in the action of the upright piano-forte and its pedal assembly. They include the elimination of the conventional hammer spring and its rail; the jack regulating rail; the jack flange; the jack stop rail; the damper flange; the back check and its wire; the bridle strap and its wire; the abstract (sticker) and its rail with guide arm; the wippen; the wippen spoon; the key frame; also the attending screws, felts and other accessories thereto. It is also intended to eliminate or substantially reduce the friction caused by the conventional arrangement of the several members so as to attain superior repetition and ease of operation; to accelerate their assemblage; facilitate their replacement and, in general, to attain economy in time, labor, material and ultimate costs. Another factor is the ability to install this action within an over-all height of a piano where this makes it a desideratum that said height be not more than 40". Other features of my invention will appear from the following specification and accompanying drawings.

Fig. 1 illustrates one adaptation of my invention, being a side elevational view, combining the positions of rest and of operation.

Fig. 2 illustrates another adaptation of my invention, as a side elevational view, with the jack sliding against an inclined buttrail and the wippen attached beneath the butt rail.

Fig. 3 illustrates yet another adaptation of my invention, in that the wippen is entirely eliminated, placing the jack directly on the piano key without the intervention of the conventional jack flange or the wippen.

Fig. 4 illustrates a perspective view of a fragmentary section of the butt rail with my damper rail positioned thereon with a damper stem removed and a damper stem positioned.

Fig. 5 illustrates another perspective view of a fragmentary section of a jack and its tripping or escapement member.

Fig. 6 illustrates another perspective view of a fragmentary section of a piano key having the jack and jack spring attached thereon with means for attaining escapement of said jack from a butt rail while affixed to said jack.

Fig. 7 illustrates a perspective view of the hammer, hammer shank, hammer butt and the brake or checker spring assembly positioned on said butt.

Fig. 8 illustrates a side elevational view of the complete loud pedal assembly according to my invention.

2

Fig. 9 illustrates a side sectional elevation of the damper's shifting rod being operated by a fulcrumed wedgeable member.

Fig. 10 illustrates a fragmentary section, in a top plan, of my method to fasten the pedal within a forked protuberance integral of a metallic piano frame.

Fig. 11 illustrates a fragmentary section, in a side elevation, of my method for positioning the holding members of the pedal.

Fig. 12 illustrates a top plan view of the holding member for the wedge shaped operating member as fastened to the key bed.

Fig. 13 illustrates a fragmentary section of a top plan view with the damper's shifting rod at rest.

Fig. 14 illustrates the same, in operation.

Like letters and numerals refer to like figures and members.

Description

1 is a piano key having its posterior extremity suitably arched or otherwise shaped at 1a to deflect an adjoining member. 2 is eyeletted arm of the lost motion regulator button 2a which constantly rests upon the key 1. 3 is the wippen which hinges on the pin 4 of the flange 6 which, in turn, is held by the screw 5 to the butt rail 31. 7 is the jack which hinges on the pin 19 and moves within the concaved depression 20 of the wippen 3. 8 is the jack heel under which the jack spring 9 exerts its pressure. 10 is the concaved recess (Fig. 5) aside which the escapement arm 40 passes then imbeds its threaded terminal into the butt rail support 31 and its other terminal retains the moveable button 40a which can be raised or lowered thereon to a given height. The bifurcated head of the jack 7 is divided into two projections; the posterior 11 which, when at rest, constantly rests against the felted seat 70 of the hammer butt 71; the anterior or frontal projection is the felted surface 13 divided from the other by the space 12 and comes into contact with the back check 14, the threaded arm 14a of which traverses the back check spring 15. This spring is adjustably positioned on the said butt 71 because of the slots 15a and positionally held thereon by the screws 16 (Fig. 7). The free end of this checker spring is made so as to have its terminal bend against itself thereby presenting an increased surface area for the threads of the arm to traverse. The hammer butt 71 hinges on the pin 18a of the flange 18 which, in turn, is positioned to the butt rail 31 by the screw 18b. The hammer shank 17 is integral with the butt 71 its base

having a greater girth than its insertable top end 78 (Fig. 7). The hammer shank rests on the hammer rail 21. 22 is the screw which positions the double spring 24—25. The posterior section of it 24, having greater strength, exerts its pressure against the damper stem 27 while the anterior or front section 25, being of lesser strength, exerts its pressure against the shank 17 or butt 71. My object is to eliminate the conventional hammer spring rail from which are suspended the hammer springs since it is very difficult, if not impossible, to replace said springs, without dismantling the entire spring assembly. 26 is the conventional damper head resting against the piano string 14. Its threaded stem 15 screws within the said stem head 28a which I make in a manner so as to have its terminal end bend against itself thereby presenting a greater area of threads into which the other member is attached.

The main damper stem 28 has a section thereof, intermediate its length, partially punched out so as to form the tongue 29, Fig. 4, the upper shoulder of which is suitably shaped at 29a so as to engage, and remain hinged upon, the damper rail 38a. This arrangement permits the curved extremity 39 of said tongue to rest and press against the butt rail 31 and, as it possesses flexibility, acts as a co-damper spring in assisting the damper to resume its position of rest against the string 14. This arrangement greatly facilitates the assemblage of a damper in that all that is required is to press it downwardly, by means of this tongue, on to the damper rail 38a after which it automatically seats and positions itself. The lower extremity of the damper stem 28 has a curved shape at 28b; my object is to have this entire damper assembly become deflected or deviated from its position of rest by that portion 1a of the piano key 1 which, sliding against said bend, attains said object. This arrangement also eliminates the conventional wippen spoon which, at present, causes the damper to become deflected. The escapement of the jack 7 from the butt 71 is attained by the jack tripper or escaper 40 (Fig. 5) positioned along the side of said jack within a side depression (concaved) of said jack 10 and its regulator button 40a. This button, being threaded on the arm 40 is utilized to accurately graduate the degree and rapidity of said escapement by increasing or decreasing the distance between it and the jack heel 8 which, when in operation, becomes tripped by said button.

Now, in Fig. 2, I attain the object of escapement of these members by screwably inserting the tripper or escaper arm 32a thru the jack 7, attaching the button 32 on one terminal. In this adaptation, I make the face of the butt rail 31 (Fig. 4), at the point 68 inclined and smooth against which the escaper button 32 slides upwardly when the jack is activated because of the depression of the key 1. In this arrangement, as in that of Fig. 1, I attain the complete elimination of the conventional jack regulating rail, the jack flange, and the jack stop rail. To increase the functional leverage of the wippen 3, I now place the wippen's flange 6 underneath the butt rail 31.

In Fig. 3 is the third adaptation of my invention in that I place the jack 7 within a recess 43 of the key 1 at which point I increase its area by having the key assume the bulge 35 thereby attaining greater rigidity, and hinge the jack on the pin 36. In this adaptation, the escaper arrangement is similar to that used in Fig. 2. In this

adaptation I also eliminate the use of the conventional key frame and place the guide pins, balance pins, key felt strip and the keys directly upon said bed. In this manner, the bed may be made to serve the purpose of a bed and of a frame, the whole being a mountable separate unit; my object is to attain a yet lower over-all height of the piano without sacrificing the height of essential members of an action, such as the lengths of hammers. Here I regulate the lost motion between key and action by the motion regulator screw 37 traversing, vertically, the key 1 near the base of the fly and, at its lower extremity, holding the regulative button 37a upon the key bed felt 37b. I also attach the jack spring 33 to the key 1 on the pin 33a. This jack spring, being a straight member, has a bend, intermediate its length (Fig. 6), and avoids any friction with the escaper arm 32a; it then resumes its straight course, upwardly, until its curved stem rests upon the felted area 42 of the recess 41. To prevent this jack from flopping backwards, when this key assembly is removed, I provide a jack-stop 44 with a felted surface 45 within the key's recess 43.

25

Operation

Fig. 1.—Depressing the key 1 raises the wippen 3 through the regulator 2a which impels the jack 7 upwardly, its projection 11 then sliding along the butt's felted seat 70 causing the hammer assembly to move towards the piano string 14. On the rebound therefrom, the checker button 14 contacts and firmly engages the jack's projection 13, after the key end 1a has deflected the damper assembly at 28b. Because of the metallic flexibility of the checker spring 15, any "chattering" or other oscillatory motion inherent from the rebound of said hammer assembly is absorbed. This arrangement eliminates the conventional back check and its wire, the bridle strap and its wire, etc. This engaged position of all the described members continues until the release of the key, when they then become disengaged and resume their respective positions of rest, with the shank finally resting upon the hammer rail 21, and the damper against the string 14 because of the exerted pressures of springs 24—25.

In Fig. 2, these movements are attained substantially in the same manner excepting that the escapement of the jack 7 is attained by the escaper button 32, becoming deflected by the fluted face 68 of the butt rail 31. The degree and accuracy of this escapement is regulated by the threaded rod 32a of the escaper member. The advantage I claim for my straight jack spring 33, when compared with the conventional coiled spring 9 is that, because of its elongated structure, permits its free terminal, because of its length, to position itself much nearer the head of the jack thereby attaining a more positive pressure and more rapid movement for the jack head to resume its position of rest. In Fig. 3, the operation of all members is substantially the same excepting that they are now accomplished without the intervention of a wippen 3 and the regulation of any lost motion occurring between the key 1 and the butt 71 is attained by raising or lowering the threaded member 37 which constantly rests upon the key bed 62. In all these adaptations of my invention, the damper assembly remains constant in its structure; its upper part 28 (Fig. 4), has the partially punched out section 29 forming the tongue, the upper portion or shoulder 29a being suitably curved and felted as to engage the damper rail 38a when this whole

damper assembly is pressed downwards; then the tongue's lower portion, suitably bent at 39 then rests upon, and presses against, the butt rail 31 from which it transmits some pressure thereby acting as a partial damper spring. In Fig. 7, the free end 78 of the hammer shank is conventionally affixed to the hammer 79. The damper assembly, as illustrated in Fig. 4, clearly shows a damper is about to be downwardly moved and also when positioned and ready to become operated.

Fig. 7 also illustrates the checker spring 15 with its slots 15a, said slots permitting the adjustment of said spring thereby regulating the degree of adhesion and the force of checking contact made between the checker button 14 and the jack's head 13. In Fig. 8 we see the butt rail 31 with a fleted portion 31a and the damper's shift rod 30 attached thereon. Between these two members passes the head of the member 48a (Fig. 9). The stem 48 of this wedgelike member has a slot 48b intermediate its length through which passes the pin 64. The lower extremity of this stem 48 hinges upon the pin 49 which is affixed to the rocker 50. This rocker fulcrums on the pin 52 of the flange 51 which, in turn, is affixed to the under side of the key bed 62. The free end of this rocker has the pin 53 to which is attached the clevis 54 of cable 55 and this, in turn, is held by the turn buckle 56, the lower end of which holds the cable section 55a which finally is anchored on the pin 57b of the pedal 57a. The end of this pedal 57a (Fig. 10) is inserted between the lugs 59 and 59a of the piano frame 61. This pedal is held by the screws 58-58a traversing the projections 59-59a, said screws, in turn, being held by the set screws 60 (Fig. 11). In Fig. 12 there is illustrated the shifting wedge stem 48 enveloping the pin 64 which is held by the cotter pin 64a and the yoke 63 so as to permit the bracket 66 to pass thru it while the arm 63a, together with the screws 65, hold said yoke. Finally, Figs. 13 and 14 show the damper shifting rod 30 which has a suitably arched bend intermediate its length, permitting the displacer wedge 48a to insert itself between said rod and the butt rails seat 31a, all being in a position of rest and the wedge having inserted itself, deflected the rod 30 and becoming effective against the damper stems 28.

Having described, illustrated and specified my invention, what I claim as new, useful and novel is:

1. Apparatus of the kind described comprising a butt rail support, a hammer movably mounted thereon, a key, parts between the key and the hammer to actuate the latter, a damper having a stem attached thereto, a second stem screwed to the first-named stem, the last-named stem extending into proximity with the key, the key and said stem having portions adapted to engage when the key operates the hammer, the second-named stem having a tongue, and the rail having means hingedly engaged by said tongue, and spring members attached to the rail between the hammer and damper.

2. Apparatus of the kind described comprising a butt rail support, a wippen pivotally attached to the lower part of the support, a jack pivotally connected to the wippen, a hammer pivotally mounted on the support above the jack, a curved spring carried by the hammer, and a check member mounted in the spring to arrest the disengaging movement of the jack, spring means engaging the wippen and a heel on the jack,

said support also having a fly tripper extending through the jack into proximity to said heel.

3. Apparatus of the kind described comprising a butt rail support, a wippen pivotally attached to the lower part of the support, a jack pivotally connected to the wippen, a hammer pivotally mounted on the support above the jack, a curved spring carried by the hammer, and a check member mounted in the spring to arrest the disengaging movement of the jack, said spring means extending straight between said jack and wippen and said jack carrying a tripper extending towards said support.

4. Apparatus of the kind described comprising a butt rail support, a hammer pivotally mounted thereon, a key, a jack pivotally mounted at one end on said key and extending towards the hammer, a straight spring on the key engaging the jack and a tripper arm carried by the jack and extending towards the support, means for cushioning the key, a spring carried by the hammer, and a member carried by the spring to arrest the movement of the jack when disengaging the key.

5. Apparatus of the kind described comprising a butt rail support, a wippen pivotally attached to the lower part of the support, a jack pivotally connected to the wippen, a hammer pivotally mounted on the support above the jack, spring means between the wippen and the jack, a curved spring carried by the hammer, and a check member mounted in the spring to arrest the disengaging movement of the jack, and a tripper for the jack, the wippen also having an adjustable regulator button resting upon said key.

6. Apparatus of the kind described comprising a butt rail support, a wippen pivotally attached to the lower part of the support, a jack pivotally connected to the wippen, a hammer pivotally mounted on the support above the jack, spring means between the wippen and the jack, a curved spring carried by the hammer, and a check member mounted in the spring to arrest the disengaging movement of the jack, and a tripper for the jack, the end of the jack adjacent the hammer being bifurcated.

7. Apparatus of the kind described comprising a butt rail support, a hammer mounted thereon, a jack and key for actuating the hammer, the latter comprising a shank with a butt having a curved cushioned surface in proximity with the jack, the hammer also having a curved check spring adjustably secured thereto, and an adjustable member carried by the spring adjacent the end of the jack which engages the hammer butt.

8. Apparatus of the kind described comprising a butt rail support, a hammer movably mounted thereon, a jack to actuate the hammer, and a key having a slot in which the lower end of the jack is pivotally mounted, the edges of the key along said slot overlapping adjacent the end of the jack.

9. Apparatus of the kind described comprising a butt rail support, a hammer mounted on the support, said support having a plate on its top, an aperture in said plate, a damper having a stem with a tongue which hingedly engages said aperture, the lower end of the tongue pressing against said support, a key to actuate the hammer and said damper.

10. Apparatus of the kind described comprising a key bed, a yoke-shaped frame thereon, a pin carried by said frame, a stem member slidably mounted on said pin, the upper end of said stem

being wedge shaped, a shifter rod engaged by said end, and a pedal having connections to actuate the stem member.

11. Apparatus of the kind described comprising a key bed, a yoke-shaped frame thereon, a pin carried by said frame, a stem member slidably mounted on said pin, the upper end of said stem being wedge shaped, a shifter rod engaged by said end, and a pedal having connections to actuate the stem member, said connections comprising a rocker on the key bed connected to the stem member, and parts joining said rocker to the pedal.
